ALBUM

George C. Sziklai, Princeton, N. J., assignor to
 Radio Corporation of America, a corporation
 of Delaware

Application February 17, 1945, Serial No. 578,395

8 Claims. (Cl. 281—32)

1

This invention relates to albums and particularly to albums for comparatively heavy and fragile articles, such as phonograph records, photographic plates and the like.

An object of the invention is to provide simple means for identifying the contents of an album without opening the album or removing it from the shelf or other support at which it is located.

Another object is to provide an improved album pull by the use of which the album may be removed from its shelf without fraying, damaging or otherwise abusing the back or binding of the album, as frequently happens with conventional albums.

A third object is the provision of an improved album with a combination index and album pull.

These objects are achieved by the invention, an embodiment of which is illustrated in the accompanying drawing in which:

Figure 1 of the drawing is a view in perspective of an album according to the invention with the index in the closed or retracted position,

Figure 2 is a view similar to Fig. 1, but with the index partly withdrawn for inspection,

Figure 3a is a view in detail of a portion of the index of Figs. 1 and 2,

Figure 3b is a view in detail of a portion of the album of Figs. 1 and 2. This figure is on the same scale as Fig. 3a and shows by projection lines the relative dimensions of the elements of the two figures,

Figure 4 is a view in detail of a portion of an album according to the invention and illustrates a modification of the arrangement shown in Figs. 1 and 2,

Figure 5 is a view in section taken along the line V—V of Fig. 4, and

Figure 6 is a view in detail of an alternative embodiment of the invention.

Referring to the drawing, an album 10 for phonograph records and the like has a back 12, at one end of which there is a plate including a slot 14. As best seen in Fig. 3b the slot consists of two connecting portions, one of which 14a is wider than the other 14b.

In a space behind the back is an index 16 which may be of parchment or of a similar sturdy material. Identifying markings on the index provide an indication of the contents of the album. For example, if the album contains records, the titles of the records and other information about them may be written or printed on the index.

A rubber or elastic band 30 is connected to one end of the index and secured within the back 12 by any appropriate means, such as rivets 26. The

2

index passes down and inside the back and is received within the slot 14. Because of the elastic band, the index is held in a normally retracted position within the back of the album. In place of the band, any appropriate biasing means may be employed, for example, springs or spring rollers as commonly used with window shades.

A cross bar 20 and a ring or pull 22 are connected to the end of the index remote from the band 30. As may be seen from the projection lines connecting Figs. 3a and 3b, the length of the cross bar is greater than the width of the slot portion 14b, but less than that of portion 14a. The pull 22 includes a part 24 (which may be regarded as a second cross bar) having a length greater than the width of slot portion 14a. The part 24 is shown in the drawing as discrete from the pull and the cross bar 20, but the three elements 20, 22 and 24 may all be made integral or discrete as desired.

The index is normally withdrawn in the space behind the back 12 by the band 30. The cross bar 20 is able to pass the wider slot portion 14a and is, therefore, also withdrawn in the space behind the back. The part 24, however, being longer than the slot portion 14a, prevents retraction of the pull so that, when the back of the album is regarded the pull alone is visible.

To identify the contents of the album, it is not necessary to open it or to remove it from its shelf or other support. By pulling downwards on the ring the cross bar 20 is made to pass through slot portion 14a and the index is withdrawn for inspection. If it is desired to remove the album the index is permitted to be retracted within the back by the force of the band 30, and the ring is pulled slightly upwards. The cross bar 20 cannot pass through the smaller slot portion 14b and the pulling force exerted removes the album from its shelf. Instead of using a metal plate for the slot, metal strips or other stiffening may, if desired, be provided around the edges of the slot 14. Without an arrangement such as here described, the back or binding of a conventional album is frequently frayed or otherwise damaged when it is pulled to remove the album from a shelf.

The index may, if desired, be made detachable from the back of the album, as for example, by the provision of hooks 28, as shown in Figs. 4 and 5, so that on changing the contents of an album, another index with different identifying markings may be substituted. In place of the hooks 28, snap rings or any similar detachable securing means may be substituted. Other modi-

fications within the scope of the invention will suggest themselves. For example, the slot 14 may be at the top of the album back and the index secured at its lower end. In this case, all the elements described will be in reverse order; the index will be pulled upwards for inspection and the ring pulled downwards for removal of the album. The pull may be of any appropriate design; for example, it may be of such a shape as of itself to prevent retraction within the slot, in which case the part 24 may be dispensed with.

The invention may be applied to binders or to any type of book-like device, as well as to albums.

There has thus been described a spring-biased index normally held in a retracted position within the space behind the back of the album, the index including a pull for removal of the album from its support.

An alternative embodiment is illustrated in Fig. 6. In this embodiment the slot 14 has only one portion instead of the two portions 14a and 14b of different size, as in Figs. 1-3. A cross bar 34 having a greater dimension than the slot is secured to the top of the index. The index may be withdrawn for inspection by pulling downwards on the ring 22, as in the previous embodiment. To remove the album from its support, however, it is not necessary in this embodiment to permit the index to be retracted within the space behind the back 12. A continued downward pull on the ring 22 causes the cross bar 34 to engage the plate surrounding the slot 14 and force is thus applied to remove the album. It is desirable in this embodiment that the index be of particularly sturdy material, such as cloth or parchment. The ring 22 should be of such shape and size as to prevent its retraction within the slot, or the cross bar 34 longer than the slot may be provided for the same purpose.

I claim as my invention:

1. An album having a back provided with a slot, said slot having two connecting portions of different widths, an index comprising a strip of flexible material adapted to pass through said slot and secured within said back, bias means for maintaining said index in a retracted position behind said back, and means connected to an end of said index for withdrawing the same through said slot and for moving said album, said last-mentioned means including a pull and a cross bar whose length is intermediate the widths of said slot portions and a connecting segment positioned between said pull and said cross bar having a width less than the narrower of the said two connecting portions of said slot.

2. An album according to claim 1, characterized in that said index is detachably secured within said back.

3. An album having a back provided with a slot, said slot having portions of different widths, an index comprising a strip of flexible material adapted to pass through said slot, spring means connected to an end of the index and secured within said back, a cross bar connected to the other end of said index, said cross bar having a length intermediate the widths of said slot portions, a pull connected to said cross bar through a connecting means narrower than the narrowest of said slot portions.

4. An album having a back provided with a slot, an index comprising a strip of flexible material adapted to pass through said slot and

secured behind the back of said album, bias means for maintaining said index in a retracted position behind said back, means for withdrawing said index through said slot in one direction, and means attached to said index for preventing withdrawal of said index through said slot in another direction.

5. An album having a back provided with a slot, said slot having two connecting portions of different widths, an index comprising a strip of flexible material having an attaching end and a pulling end, adapted to pass through said slot and secured by said attaching end adjacent one end of said back, bias means for maintaining said index in a retracted position behind said back, a cross bar connected to said pulling end of said index and having a length intermediate the width of said slot portions and a pull including a member connected to the cross bar and having a dimension greater than the width of either of said portions, said member being connected to said cross bar through a linking segment having a width narrower than either of said slot portions.

6. An album having a back provided with a slot, said slot having portions of different widths, an index comprising a strip of flexible material adapted to pass through said slot, elastic means connected to an end of the index and secured within said back, a cross bar connected to the other end of said index, said cross bar having a length intermediate the widths of said slot portions through a segment having a width narrower than the width of any of said slot portions, and a pull connected to said cross bar, said pull including means to prevent its retraction within said back.

7. An album having a back provided with a slot, said slot having two connecting portions of different widths, an index comprising a strip of flexible material adapted to pass through said slot and being normally positioned within said back, and means connected to an end of said index for withdrawing the same through said slot and for moving said album, said last-mentioned means including a pull and a cross bar having a length intermediate the widths of said slot portions, said pull being connected to said cross bar through a segment having a width narrower than the width of either of said slot portions.

8. An album having a back provided with a slot, an index comprising a strip of flexible material adapted to pass through said slot and secured behind the back of said album, bias means for maintaining said index in a retracted position behind said back, a pull connected to said index for withdrawing said index through said slot, means for preventing retraction of said pull through said slot, and means connected to said index for preventing complete withdrawal of said index through said slot.
